UNITED STATES PATENT OFFICE.

FRANK L. DODGSON, OF ROCHESTER, NEW YORK, ASSIGNOR TO GENERAL RAILWAY SIGNAL COMPANY, OF GATES, NEW YORK, A CORPORATION OF NEW YORK.

RAILWAY SIGNALING SYSTEM.

1,352,793.

Specification of Letters Patent. Patented Sept. 14, 1920.

Application filed July 1, 1916. Serial No. 107,019.

To all whom it may concern:

Be it known that I, FRANK L. DODGSON, a citizen of the United States, and a resident of the city of Rochester, in the county of 5 Monroe and State of New York, have invented new and useful Improvements in Railway Signaling Systems, of which the following is a specification.

This invention relates to railway signaling 10 systems and more particularly to such systems using normally closed track circuits.

The main objects of my invention are to insure the intended operation of the track relays under all of the varying conditions 15 of practice, both as regards the deenergization of the relays so as to insure the dropping of the relay armatures and also as regards the proper energization of the relays and movement of the armatures to their normal raised position; and the accomplishment 20 of these results with a minimum expenditure of energy in the track circuits. My invention fulfills these objects, giving certainty of proper operation under all conditions in 25 an economical and efficient manner. Other objects and advantages which are obtained by my invention will be understood by those skilled in the art.

One factor of difficulty with track circuits 30 is the variation in ballast resistance which occurs under practical service conditions and another difficulty is the variation in the amount of the shunt resistance when a train is in the block section, which shunt 35 path should of course always cause the deenergization of the relay so as to cause it to drop its armature. The resistance of the shunt path formed by the presence of a car in the block, not only varies relatively to 40 the relay according to the position of the train in the block, but also depends upon the condition of the surface of the rails and car wheels, the presence of rust, or scale, and the like causing variation of the shunt 45 resistance.

Another factor affecting the operation is that when the relay armature is in its lowest position, the energy in the relay coils which is necessary for moving the armature 50 to its attracted position is greater than the energy which is necessary to retain the armature in its attracted position. This results in the expenditure of considerable energy when the armature is in its normal

position and also necessitates such a low 55 shunt resistance to insure the deenergization of the relay sufficiently for causing its armature to drop, that the relay under some conditions fails to act upon the entry of a train in the block section. 60

It has been proposed to insert a resistance in series with the relay coil by control of its relay contacts when the relay armature leaves its lowest position, but this has proven of no practical utility, because if the amount 65 of the resistance is sufficient for securing any practical advantage in overcoming the above difficulties, it results in a continuous vibration of the relay armature when no train is in the block section, especially under conditions of low ballast resistance with resultant 70 low voltage at the relay. This is because the armature as soon as it leaves its back contact inserts the resistance in the circuit of the relay coil and consequently so reduces 75 the strength of current through the relay coil that it is not sufficient to complete the movement of the armature to its attracted position resulting in the armature dropping to its lowest position; this in turn cuts out 80 the resistance, causing the current strength in the relay coil to be sufficient to again raise the armature, which then falls, due to the insertion of the resistance, and so on giving a vibratory movement which of course renders 85 the suggestion useless for any practical service.

It has also been proposed to utilize the two coils of the relay in a series and parallel connection relatively to each other, utilizing 90 the parallel connection of the coils when the relay armature is in its lowest position and for raising the armature to its attracted position, and utilizing the series connection of the coils for retaining the armature in its attracted or raised position. This has proven to be of no practical benefit, because when the relay coils are properly wound in relation to the track circuit voltage, the ballast 95 resistance and shunting resistance of the 100 train for properly picking up the armature upon the exit of a train from the block section, the series connection of the coils then gives such a reduced amount of energy for holding the relay armature, that it is insufficient, especially when under variation of 105 the ballast resistance the voltage at the relay has become comparatively low. The result

is that the armature will drop as soon as the series connection of the coils is made, even though it be not made until the armature is placed in its final attracted position; 5 the dropping of the armature results in placing the relay coils in parallel which again raises the armature and places the coils in series causing the armature to again drop, thus giving a continuous vibration of the 10 relay armature which of course renders this arrangement totally useless for practical application to the closed track circuit system.

By my invention these difficulties are entirely overcome and the objects and advantages fulfilled as above stated.

My invention will be understood by reference to the following description and the accompanying drawings, in which—

Figure 1 is a diagrammatic illustration of 20 one embodiment of my invention, and Fig. 2 is a diagrammatic illustration of a modified form of my invention.

Referring first to the embodiment of the invention shown in Fig. 1; the numerals 1 25 and 2 designate the track rails of a track section or block A, the separate rail sections thereof being suitably bonded together in the well known manner, and being separated from the track rails of the adjacent track 30 sections or blocks by insulating joints 3. A source of electro-motive force, illustrated as a battery 4, is connected across the track rails 1 and 2 near one end of the block A, and at the other end of said block a track relay 35 R has one terminal of its coils or windings connected by a conductor 5 to the track rail 2, the other terminal of the coils of said track relay being connected by conductor 6, adjustable resistance 7, and conductor 8 40 to the track rail 1.

Associated with the track relay R is an auxiliary relay 9 having the usual armature which controls two contact fingers shown conventionally in the drawing and designated 10 and 11. In this connection it is noted that relays are ordinarily provided with only one armature, properly speaking, which armature is connected to and operates any number of contact fingers desired; but 50 it should be understood that a relay may have two or more armatures, each controlling a circuit, and in the description herein-after given the words contact finger are intended to include a separate armature. The 55 contact finger 10 governed by the auxiliary relay 9 controls a shunt path of relatively low resistance around the resistance 7, said shunt path comprising conductor 12, contact finger 10 in its lower position and conductor 13. The contact finger 11 of the auxiliary relay 9 is shown as controlling a signal S for governing traffic over the block A, said signal being shown as the normally clear type and having a controlling circuit 60 which may be traced as follows: commenc-

ing at the battery 14, conductors 15 and 16, contact finger 11 in its upper position, conductor 17, operating mechanism of the signal S (not shown) and conductors 18 and 19 back to the battery 14.

The track relay R is shown as provided with the single armature or contact finger 20 which controls the circuit for energizing the auxiliary relay 9, which circuit may be traced as follows: commencing at the battery 14, conductors 15 and 21, auxiliary relay 9, conductor 22, armature 20 in its upper position and conductors 23 and 19 back to the battery 14.

Referring to the operation of the embodiment of the invention illustrated in Fig. 1, the parts are shown in the position which they assume when no train is present in the block A, the armature 20 of the track relay R being in its upper position, the auxiliary 80 relay 9 being energized, and the resistance 7 being included in the connections between the track relay R and the track rails 1 and 2.

When a train enters block section A, the armature 20 of the track relay R drops and 90 interrupts the circuit hereinbefore traced for energizing the auxiliary relay 9, thereby causing the contact fingers 10 and 11 of said relay 9 to drop to their lower position. The deenergization of the auxiliary relay 9 may 95 be used to control any suitable signaling device, or may be used to perform any desired function; but in the particular arrangement shown in Fig. 1, the dropping of the contact finger 11 of said relay 9 interrupts the circuit 100 for the operating mechanism of the signal S, thereby causing the signal S to assume its biased position and indicate stop or danger.

When the contact finger 10 of the auxiliary 105 relay 9 drops it establishes a relatively low resistance shunt path around the resistance 7, so that the resistance 7 which was formerly included in the connections between the track relay R and the track rails 1 and 110 2, is now excluded from said connections; and when the train leaves the block A the connections between the relay R and the track rails 1 and 2 include the minimum amount 115 of resistance, so that sufficient current can be derived from the minimum electro-motive-force impressed upon the track rails 1 and 2 at the location of the battery 4, to to sufficiently energize the relay R to raise its armature 20 from its lower position to its 120 upper position.

When armature 20 reaches its final upper position, and not before, it energizes relay 9 which in turn raises its armatures or fingers 10, 11, causing the resistance 7 to be 125 inserted in series with track relay R and also causing the signal S to be moved to its proper position.

Adjustment of the resistance 7 to a proper amount is important in securing the full 130

advantage from the utilization of my invention. By reason of the fact that the resistance is short circuited when the track relay armature is in its lowest position, 5 and remains short circuited until the track relay armature has been fully raised to its uppermost position, it offers no impediment to the economical utilization of the energy from the track circuit in the track 10 relay for raising its armature as soon as the car or train has passed out of the block section. For insuring the proper raising of the armature the relay must be properly wound and proportioned in relation to the 15 track circuit and the value of the electro-motive-force impressed upon the track circuit must be adjusted to insure the raising of the armature under the worst ballast conditions. The resistance 7 is then adjusted 20 to an amount so that when no train is in the block and the track relay armature is in its raised position, the current flow will be just sufficient to insure the holding of the armature of the track relay 25 in its upper position, due allowance, as may be found desirable, being made for variations in ballast resistance, variations in voltage applied to the portion of the circuit containing the track relay and other conditions 30 which may occur in practice.

It is evident that with these conditions the amount of energy consumed in holding the relay armature in its upper position when no train is in the block is much reduced 35 compared with the amount which would be necessary if the resistance 7 were not utilized, thereby securing economy of energy when no train is in the block. Furthermore it is necessary to shunt only a 40 small part of the current flowing in the coils of the track relay in order to cause its armature to drop. Consequently when the train enters the block, although the track rails may be rusted or dirty, or other conditions 45 may be such that the resistance of the shunt established by the wheels and axles of the train is comparatively high, nevertheless, sufficient current will be shunted from the coils of the track relay to insure 50 the dropping of the track relay armature under all the variable conditions of practice, thus giving certainty of proper operation of the signals.

In the modification shown in Fig. 2 the 55 function performed by the contact finger 10 of the auxiliary relay 9 is performed by a circuit controller 24 operated by the signal S. This circuit controller 24 is illustrated conventionally, and is closed when 60 the signal S is in its horizontal or danger position, so that when the block A is occupied by a train and the signal S is in its horizontal position, the circuit controller 24 is closed and establishes a relatively low 65 resistance path comprising conductors 25

and 26, and the circuit controller 24, around the resistance 7. The resistance 7 shown in Fig. 2 is determined and adjusted in the same manner as hereinbefore described in connection with the resistance 7 shown in Fig. 1. In the arrangement shown in Fig. 2, the armature 20 of the track relay R controls the signal S by means of a circuit which may be traced as follows: Commencing at the battery 27, conductor 28, armature 20 in its upper position, conductor 29, operating mechanism of the signal S and conductor 30 back to the battery 27.

The operation of the modified arrangement of circuits and controlling devices 80 shown in Fig. 2 is in effect the same as the operation of the arrangement shown in Fig. 1, except that in the arrangement shown in Fig. 2 the shunt for the resistance 7 is established by the operation of the circuit 85 controller 24; whereas, in the arrangement shown in Fig. 1, the shunting of the resistance 7 is accomplished by the deenergization of the auxiliary relay 9.

It should be noted that in both of the 90 arrangements shown the resistance 7 is not included in the circuit for the coils of the track relay R until the armature of said track relay has been raised to its uppermost position, since it is evident that in the arrangement shown in Fig. 1 the armature 20 of the track relay R must be raised to its upper position before the auxiliary relay 9 is energized, and that the shunt around the resistance 7 is not broken until 100 said auxiliary relay 9 is energized and its contact finger 10 is raised. In a similar way, in the arrangement shown in Fig. 2, the armature 20 of the track relay R must be raised to its upper position before the 105 circuit for operating the signal S is completed, and it is apparent that the shunt path around the resistance 7 is not broken until the signal S is operated toward its clear position and the circuit controller 24 110 is actuated thereby.

By reason of this construction, it is assured that the resistance 7 will never be inserted in circuit with the relay coils until the armature 20 has been raised to its uppermost or attracted position. This is an important feature of this invention, since it enables the greatest advantage to be derived from the insertion of the resistance 7, and at the same time avoids the possibility 120 of the vibration of the armature 20 which characterizes the constructions heretofore suggested as a solution for the problem. In this connection, it should be understood that the amount of current needed to just overbalance the weight or bias of the relay armature varies in its different positions between the lowermost position and the uppermost position, this variation being due to the change in the air gap between the armature 125 130

and the pole pieces. With the armature of a relay in its lowermost position, the amount of current flowing in the relay coils, required to cause the armature to commence its upward movement, is the greatest; and as the air gap between the armature and the pole pieces is reduced by the approach of the armature more and more to its uppermost position, the current required to continue the movement of the armature may be decreased. As explained hereinbefore, for the purpose of economy and safety, it is desirable to reduce the current flowing in the relay coils as much as possible when the relay armature is fully raised, the ideal object sought to be obtained being that in which the current is reduced to an amount just sufficient to retain the armature in its raised position. This desirable result cannot be accomplished if the resistance is inserted in circuit with the relay coils by the armature of the relay itself, for the reason that the current cannot be reduced, when the armature is only partly raised, to the extent desired, without causing objectionable vibration of the relay armature. When, however, provision is made, as in my invention, for inserting this resistance in the circuit only after the relay armature has completed its movement to its attracted position, the resistance 7 may be adjusted to give the best results, and at the same time the objectionable vibration of the armature is avoided. Furthermore, according to this invention, there is no possibility of an objectionable vibration of the relay armature when ballast conditions become exceptionally bad, because the relay armature, if it will be attracted at all, will be held in its attracted position when the resistance 7 is inserted in circuit.

It is also characteristic of this invention that the resistance 7 is not cut out of the circuit upon shunting of the relay until the relay armature has reached its lowermost position, thereby assuring that this resistance will not interfere with the complete dropping of the armature. In the arrangement shown in Fig. 1 the resistance 7 is not shunted until after the contact finger 10 of the auxiliary relay 9 falls to its lower position, and that this will not occur until after the armature 20 of the track relay R has dropped to its lower position, providing that the time required for the dropping of the armature of the auxiliary relay 9 is the same or even slightly less than the time required for the armature 20 of the track relay R to drop to its lower position. In other words, the resistance 7 is not shunted after the energization of the track relay R and the dropping of its armature 20 until after the armature 20 of said track relay R has reached its lowermost position. The same advantages are obtained by the modified

construction shown in Fig. 2. In the arrangement shown in Fig. 2, the shunt around the resistance 7 is not established until after the armature 20 of the track relay R has dropped far enough to interrupt the circuit for the signal S, and until the signal S has assumed its horizontal or danger position and closed the circuit controller 24; and since the time required for the signal S to move from its vertical position to its horizontal position is long compared with the time required for the armature 20 of the track relay R to move from its upper position to its lower position, it is assured that the resistance 7 will not be shunted until the armature 20 of said track relay has reached its lowermost position. Also, in the arrangement shown in Fig. 2, the resistance 7 is not shunted until the signal S reaches its horizontal or danger position, that is, the operating characteristics of the track relay R are not changed until the signal S has properly responded to the control of said track relay.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In a signaling system for railways, a track circuit comprising a source of electro-motive force and a relay, a resistance external to the windings of the relay and adapted to reduce the current through the relay windings to a predetermined value corresponding approximately to that required to maintain the relay picked up, and circuit controlling means responding to the operation of the relay for inserting said resistance in series with the relay windings without interrupting the path of current through said windings, said means lagging in its operation behind the movement of the relay armature and acting to insert said resistance only after said armature has attained its fully attracted position.

2. In a signaling system for railways, a track circuit comprising a source of electro-motive force and a relay, a resistance external to the windings of the relay and adapted to reduce the current through the relay windings to a predetermined value corresponding approximately to that required to maintain the relay picked up, and circuit controlling means governed by the relay armature for inserting said resistance in series with the relay windings only after said armature has fully attained its at-

tracted position and for excluding said resistance from the path of current through said windings when the armature has fully attained its retracted position, said means 5 acting to maintain a path for current through the relay windings at all times.

3. In a signaling system for railways, a track circuit comprising a source of electro-motive force and a relay, a resistance external to the windings of the relay and adapted to reduce the current through the relay windings to a predetermined value corresponding approximately to that required to maintain the relay picked up, and 10 automatic means separate from the relay and set into operation when the relay armature fully attains its attracted position for inserting said resistance in series with said windings without interrupting the flow of 15 current through said windings.

4. In a signaling system for railways, a track circuit comprising a source of electro-motive-force and a relay, a resistance external to the windings of said relay, a movable device for controlling the inclusion and exclusion of said resistance in and from the path of the main circuit through the windings of said track relay, and means for causing said movable device to be controlled 25 upon the movement of the armature of said relay to its extreme positions.

5. In a signaling system for railways, a track circuit comprising a source of electro-motive-force and a relay, a resistance external to the windings of said relay, a second relay having its windings energized and de-energized by movement of the armature of 35 said first relay, and means controlled by said second relay for inserting and cutting 40 out said resistance from the path of the main current through said first relay.

6. In a signaling system for railways, a track circuit comprising a source of electro-motive-force and a relay, a resistance external to the windings of said relay, and means separate from the relay and controlled thereby for inserting and cutting out 45 said resistance from the path of the main current through said first relay only after the armature thereof has attained its extreme positions.

7. In a signaling system for railways, in combination: a track circuit including a section of bonded track rails and a source of 55 electro-motive force connected across said track rails at one end of the section, a track relay connected to the track rails at the other end of the section, means external to the windings of the relay and adapted to limit 60 the attractive force exerted by said windings upon the relay armature to a predetermined selected value, and means responsive to the flow of current in the relay windings for rendering said first mentioned 65 means effective only after the relay arm-

ture has attained its fully attracted position and without interrupting the flow of current through said relay windings.

8. In a signaling system for railways, a track circuit comprising a source of electro-motive-force and a relay, means external to the relay windings for limiting the attractive force of the relay upon its armature to an amount sufficient to hold the armature of said relay in its raised position but insufficient to raise said armature from its lowest position, and controlling means for causing said first named means to be effective and ineffective respectively only when the armature of said relay is in its 70 fully attracted position and in its fully retracted position, said means both acting to maintain a path for current to flow through the relay windings at all times.

9. In a signaling system for railways, the combination with a track circuit including a source of current and a relay, of an adjustable resistance external to the windings of the relay and adapted to reduce the current through said windings to a predetermined value, circuit controlling means for connecting said resistance into and out of the circuit through the relay windings without at any time interrupting the flow of current through said windings, and electromagnetic means controlled by the relay armature for operating said circuit controlling means, said electromagnetic means acting to operate the circuit controlling means only after the completion of the movement of 90 the relay armature to its extreme positions.

10. In a signaling system for railways, in combination: a track circuit including a section of track rails and a source for impressing an electromotive-force across said track 105 rails at one end of said section; a track relay having an armature; electrical connections between said track relay and said track rails at the other end of said section; means controlled by said track relay for automatically increasing the resistance of 110 said connections approximately in accordance with the difference between the pickup and holdup currents for said relay, said means acting to change the resistance only after the armature of said relay has been raised to its uppermost position and without at any time interrupting said connections; and means for signaling controlled by 115 said track relay.

11. In a signaling system for railways, a track circuit including a source of current and a relay, a resistance external to the windings of the relay and connected in series therewith, a second relay having its energizing circuit controlled by a front contact of the track relay, and a low resistance shunt for said resistance opened and closed when said second relay picks up and drops respectively.

126

125

130

12. In a signaling system for railways, a track circuit comprising a source of current and a relay, an adjustable external resistance in the connections between the track 5 relay and the track rails, a low resistance shunt for said resistance, biased electromagnetic means for opening and closing said shunt when energized and deenergized respectively, and a circuit controlling said

means and including a front contact of the 10 track relay, whereby said adjustable resistance is included and excluded from the circuit through the track relay without interrupting the path for the flow of current through the relay and only after the relay 15 armature has attained its extreme positions.

FRANK L. DODGSON.
